BY Hilmarth & Thurston
ATTY.

UNITED STATES PATENT OFFICE.

ALBERT C. WOODWORTH, OF PROVIDENCE, RHODE ISLAND, ASSIGNOR TO
THE CONSOLIDATED CAR FENDER COMPANY, OF SAME PLACE.

DESIGN FOR A CUSHION OR GUARD FOR STREET-CARS.

SPECIFICATION forming part of Design No. 30,201, dated February 14, 1899.

Application filed January 17, 1899. Serial No. 702,490. Term of patent 14 years.

To all whom it may concern:

Be it known that I, ALBERT C. WOODWORTH, of the city and county of Providence and State of Rhode Island, have invented a certain new and original Design for a Cushion or Guard for Street-Cars, of which the following is a specification, reference being had to the drawing, forming a part thereof.

The drawing is a perspective view of a cushion or guard embodying the present design.

The leading feature of the design consists in a guard or cushion of grid-like structure having return curves at the top and bottom.

The guard or cushion illustrated is formed

of a series of parallel strips A, which have return curves B at the top and bottom and are secured to longitudinal strips C.

The design provides an attractive and graceful guard or cushion which presents a characteristic and distinguishing appearance to the eye.

What I claim is—

The design for a guard or cushion, substantially as shown and described.

ALBERT C. WOODWORTH.
